FREQUENCY CHANGING RADIO
RECEIVING APPARATUSYves Rocard, Paris, France, assignor to La
Radiotechnique, Paris, France, a corporation
of FranceApplication January 15, 1932, Serial No. 586,767
In France January 22, 1931

6 Claims. (Cl. 250—20)

This invention relates to frequency changing radio receiving apparatus and makes possible the regulations of the circuit tuned to the frequency received and of the heterodyne circuit in such a frequency changing system, for example, in a superheterodyne radio telephonic receiver, entirely independent of one another. The invention has for its principal object the elimination of the amplification blanks which these receivers always present on the scale of the frequencies to be received, and enables, in a simple and practical manner, the single control of the tunings of the circuits to be effected.

Various illustrative examples of carrying the invention into effect are given below, but they are to be understood as being non-limitative, the invention being more particularly set forth in the appended claims.

The invention will now be described with reference to the annexed drawing, in which:—

Figure 1 represents the diagram of a superheterodyne circuit with dual-grid frequency changer, arranged according to the invention.

Figure 2 represents diagrammatically a special thermionic tube constructed in accordance with the invention.

In the drawing, identical references indicate the same parts.

Two examples of the undesirable phenomena which are produced when the independence of tuning of the circuits obtained in accordance with this invention is absent, will be described; actually this independent of tuning is not attained in any previously known systems.

Considering the radio modulator represented in Figure 1, there is shown a dual-grid thermionic tube 1 for effecting frequency change followed by a mean frequency filter 14. The input circuit of the control grid 2 of the tube consists generally of a frame aerial 4 tuned by a variable condenser 5. This anti-resonant circuit is thus shunted by the capacities formed between the control grid 2 and oscillating grid 3 and between the control grid 2 and the plate 6 of the dual-grid tube, each followed by the impedance which charges the corresponding electrode; it will be understood that if this grid-to-grid or grid-to-plate capacity comes into resonance-series with the charging impedance in question (which will be for example the oscillating circuit 7—3 of the heterodyne), the input circuit formed by the tuned frame aerial will be shunted by a resulting zero impedance: At the frequency for which this effect is produced the frame aerial circuit will, therefore, give no signal to the grid 2, and the receiv-

ing station will possess a "blank" spot in its tuning range. If the "beat" is changed by manipulating the heterodyne condenser 8, this effect may be avoided, but in such case an effect quite as undesirable is produced, namely the tuned frame aerial is placed in resonance-series by the capacity formed between the grid 2 and the other electrodes short-circuiting the oscillating circuit of the heterodyne.

Now, with the capacities actually formed between the electrodes of dual-grid tubes and with the order of the mean frequencies employed, these phenomena are actually produced in the range of broadcast frequencies, and they are only avoided by using the second or third harmonics of the heterodyne, a process which cannot be generally employed over the whole scale without inconvenience, for the fundamental of the heterodyne will sometimes be very close to the mean frequency, and furthermore, the amplitude of the harmonics in question varies considerably over the scale of frequencies.

In addition to the serious disadvantages described above, the interdependence or mutual reaction of the circuits always introduces a mutual dependence between the regulations of the two circuits 4—5 and 7—8 which renders the employment of a single control practically impossible, owing to the dependence being subject to sudden variation on the scale of the frequencies and of variation from one tube to another.

The present invention enables the regulations of the circuits tuned to the wave frequency to be received independent of the regulation of the heterodyne, and vice versa. By this is meant that the position of the variable member (for example, the condenser 5) which enables the receiving aerial circuit to be tuned to a carrier wave, is independent of any frequency value which is given to the heterodyne 7—8. It is established that the tunings to the carrier wave and the heterodyne follow simple and regular laws as a function, for example, of the variable capacities, which will permit a single control to be employed, and in any case eliminate the "blank spots" above referred to.

In the case of a radio modulator, a tube (for example, a dual-grid or tri-grid) is employed in which a control electrode modulates an oscillation created by the same tube. In Figure 1, such a tube is indicated at 1. In this case, the invention provides that this control electrode is surrounded by a screen 13 arranged to be subjected to a fixed potential by means of a battery 10 which will appreciably cancel the capacity of the grid 2 with respect to all the other electrodes,

namely, in the example shown, the cathode, oscillating grid and plate or anode. It will be appreciated that a plurality of screens may be employed to obtain the end in view; the principle of the invention consists generally in the practical suppression of the capacities between the control grid and the other electrodes of the tube.

Figure 2 illustrates diagrammatically in section an embodiment constructed in accordance with the invention, of a tube. The pinch of the tube is indicated at 17, the cathode at 15 (assumed on the drawing to be indirectly heated), the oscillating grid at 3, the screen at 13 serving completely to insulate the control grid 2 as above described, and the plate or anode at 6. The connection of the control grid with the external circuits will be effected by a conductor 16, the passage of which through the bulb will be removed from the zone of the connections for the other electrodes extending through the pinch 17 of the tube, and arranged for example at the top of the tube bulb.

What I claim is:—

1. In a frequency changing radio receiver, the combination of a tube having a plurality of electrodes including among others a cathode and conditioned to be traversed by an electronic flow issuing from the cathode, an oscillating circuit connected to one of said electrodes, coupling means in the circuit of another of said electrodes for coupling said last circuit together with said oscillating circuit so as to cause a predetermined radio frequency current to be locally generated in said oscillating circuit, a source of a different radio frequency connected to still another of said electrodes, capable of controlling the electronic flow, and means for suppressing the capacity between said electrode which is connected to said oscillating circuit and said last controlling electrode and the plate of said tube.

2. In a frequency changing radio receiver, the combination of a tube having a plurality of electrodes including among the same a cathode and conditioned to be traversed by an electronic flow issuing from the cathode, an oscillating circuit connected to one of said electrodes, coupling means in the circuit of another of said electrodes for coupling said last circuit together with said oscillating circuit so as to cause a predetermined radio frequency current to be locally generated in said oscillating circuit, a source of a different radio frequency connected to still another of said electrodes, capable of controlling the electronic flow, and a screen interposed between said electrode which is connected to said oscillating circuit and said last controlling electrode and the plate of said tube.

3. In a frequency changing radio receiver, the combination of a tube having a plurality of electrodes including among the same a cathode and conditioned to be traversed by an electronic flow

issuing from said cathode, an oscillating circuit connected to one of said electrodes, coupling means in the circuit of another of said electrodes for coupling said last circuit together with said oscillating circuit so as to cause a predetermined radio frequency current to be locally generated in said oscillating circuit, a source of a different radio frequency connected to still another of said electrodes, capable of controlling the electronic flow, a screen interposed between said electrode 10 which is connected to said oscillating circuit and said last controlling electrode and the plate of said tube, and means for subjecting the screen to a predetermined potential.

4. In a frequency changing radio receiver, the combination of a tube having a plurality of electrodes including among the same a cathode and conditioned to be traversed by an electronic flow issuing from said cathode, at least one of the other electrodes being adjacent to the cathode, an oscillating circuit connected to said electrode which is adjacent to said cathode, coupling means in the circuit of a third of said electrodes for coupling said last circuit together with said oscillating circuit so as to cause a predetermined 25 radio frequency current to be locally generated in said oscillating circuit, a source of a different radio frequency connected to still another of said electrodes, capable of controlling the electronic flow and extending between the plate and said 30 electrode which is adjacent to said cathode, and a screen extending between said last controlling electrode and the local radio frequency electrode adjacent to the cathode.

5. In a frequency changing radio receiver, the combination of a tube having a plurality of electrodes including among the same a cathode and conditioned to be traversed by an electronic flow issuing from said cathode, an oscillating circuit connected to another of said electrodes, coupling 40 means in the circuit of a third of said electrodes for coupling said last circuit together with said oscillating circuit so as to cause a predetermined radio frequency current to be locally generated in said oscillating circuit, a source of a different 45 radio frequency connected to still another of said electrodes, capable of controlling the electronic flow, there being a plate, and a screen extending between said last controlling electrode and the third or local radio frequency electrode and 50 also between said controlling electrode and the plate.

6. An electronic tube according to the combination in claim 1, wherein the controlling electrode passes through the top of the envelope or bulb, while the other electrodes including at least the cathode, plate, local radio frequency electrode and screening electrode are connected to leads extending through the pinch of the tube.
